UNITED STATES PATENT OFFICE

134,922

DESIGN FOR A COLLECTING RECEPTACLE FOR GRINDINGS OR THE LIKE

Fred E. Hart, Southgate, Calif.

Application August 29, 1942, Serial No. 108,073

Term of patent 14 years

To all whom it may concern:

Be it known that I, Fred E. Hart, a citizen of the United States, residing at Southgate, in the county of Los Angeles and State of California, have invented a new, original, and ornamental Design for a Collecting Receptacle for Grindings or the like, of which the following is a specification, reference being had to the accompanying drawing, forming part thereof.

Figure 1 is a perspective view of a collecting receptacle, showing my new design; Fig. 2 is an

end elevational view of the disclosure shown in Fig. 1; Fig. 3 is another end elevational view looking at the opposite end from that shown on Fig. 2; and Fig. 4 is a central longitudinal section taken on the line 4—4 of Fig. 2.

I claim:

The ornamental design for a collecting receptacle for grindings or the like, as shown.

FRED E. HART.
